UNITED STATES PATENT OFFICE.

WILLIAM F. FOLMER, OF ROCHESTER, NEW YORK, ASSIGNOR TO EASTMAN KODAK COMPANY, OF ROCHESTER, NEW YORK, A CORPORATION OF NEW YORK.

AERIAL CARRIER FOR PHOTOGRAPHIC FILMS.

1,238,904.

Specification of Letters Patent.

Patented Sept. 4, 1917.

Application filed April 5, 1917. Serial No. 159,850.

To all whom it may concern:

Be it known that I, WILLIAM F. FOLMER, of Rochester, in the county of Monroe and State of New York, have invented certain new and useful Improvements in Aerial Carriers for Photographic Films; and I do hereby declare the following to be a full, clear, and exact description of the same, reference being had to the accompanying drawings, forming a part of this specification, and to the reference-numerals marked thereon.

My present invention relates to aeronautics and more particularly to parachutes and it has for its objects to provide a simple, cheap and convenient device of this character that may be successfully used to safely convey to the ground photographs or exposed photographic material taken by aviators in the course of journeys in the air. The improvements are directed in part toward making convenient and positive the spreading of the parachute when called into use and toward the container for the film spool or other photographic record and its mode of attachment to the parachute. To these and other ends the invention resides in certain improvements and combinations of parts all as will be hereinafter more fully described, the novel features being pointed out in the claim at the end of the specification.

In the drawings:

Figure 1 is a side view of my improved aerial carrier as it appears while descending with its load, the parachute being shown in section;

Fig. 2 is a longitudinal sectional view through the parachute and the case which maintains it in folded position;

Fig. 3 is an enlarged sectional view of the container for the film roll, and

Fig. 4 is a detail sectional view taken substantially on the line 4-4 of Fig. 1 illustrating the manner in which the parachute parts are held together.

Similar reference numerals throughout the several views indicate the same parts.

In a device of the nature indicated, it is desirable that provision be made for lowering the undeveloped but exposed film from the aeroplane to the earth by a gentle fall; that the film be so inclosed and protected as to insure its preservation whether it

drops on land or water, and that the device be so simple and inexpensive and compact that a number of carriers may be provided for each operator and freely used.

In the practice of my invention, I provide a parachute embodying a fabric or other light flexible web 1 stretched upon wire or other spring ribs 2 radiating from a central vertical stem 3 terminating at its lower end in a shepherd's hook 4. The pointed and roughened upper end 5 of the stem is driven into the lower end of a wooden anchor block 6 surrounded by a metal ferrule or sleeve 7. The inner ends 8 of the ribs 2 are driven into the upper end of the block and adjacent these ends the ribs are coiled at 9 to provide springs normally tending to expand them or project them laterally and stretch the web 1. But the web may be collapsed and the ribs folded to lie longitudinally of the stem 3 against the tension of the springs, as shown in Fig. 2. To hold the parachute so folded, a tubular casing 10 having a smooth interior open at both ends is slipped over it to both inclose and protect it as shown in Fig. 2. These casings may be individual or banks of them may be provided to hold a number of separate parachutes.

A roll of exposed film 11 (Fig. 3) to be carried to the earth is slipped into a cylindrical box or container 12, the flanged cover 13 of which when put in place over the open end may be secured in a water tight manner by a strip of adhesive tape 14. In the cover is an eye 15 and this eye is engaged with the shepherd's hook 4 on the parachute stem. By a subsequent pull on the latter, it is withdrawn from its tube 10 whereupon it immediately expands to the open position and the device is then ready to be thrown from the aeroplane. When the casings 10 are individual, they may be held in the hand after the attachment of the container 12 to the hook 4 and the parachute and its burden flicked out of the end thereof by a jerk of the arm which will clear the device of the aeroplane as the parachute opens.

I claim as my invention:

In an aerial carrier for photographic film spools, the combination with a folding parachute comprising a stem terminating in a spring hook, a web, and spring ribs for ex-

2
panding the latter adapted to fold under tension to lie longitudinally of the stem, of an open ended tubular case inclosing the parachute to retain the ribs in folded positions and from which the parachute may be withdrawn by means of its stem, and a fluid tight container adapted to receive the film

spool and detachably suspended from the hook of the parachute stem.

WILLIAM F. FOLMER.
